UNITED STATES PATENT OFFICE

103,217

DESIGN FOR A WASHING MACHINE TUB

Robert M. Chesney, Alliance, Ohio, assignor to
The Alliance Porcelain Products Company,
Alliance, Ohio, a corporation of Ohio

Application July 18, 1936, Serial No. 63,925

Term of patent 7 years

To all whom it may concern:

Be it known that I, Robert M. Chesney, a citizen of the United States, residing at Alliance, county of Stark, and State of Ohio, have invented a certain new, original, and ornamental Design for a Washing Machine Tub, of which the following is a specification, reference being had to the accompanying drawing, forming a part thereof.

Fig. 1 is a perspective view of a washing machine tub showing my new design; and

Fig. 2 is a plan view.

I claim:

The ornamental design for a washing machine tub as shown.

ROBERT M. CHESNEY.
